SILK SCREEN PRINTING METHOD

Franz Weiss, Chicago, Ill.

No Drawing. Application September 8, 1933,
Serial No. 688,697

5 Claims. (Cl. 101—115)

My invention relates to a silk screen printing method and more particularly to the mechanical production of shaded or half-tone silk screens (plates).

5 An object of the invention is to prepare shaded or half-tone silk screens, without the use of photography, and by employing engraved or etched plates; a further object is to produce shaded effects on thin transparent papers which 10 may be used directly as negatives for preparing screens. Another object is to provide a method for the easy and quick making of drawings or designs with shaded effects on thin papers for advertising cuts and the like. Other objects 15 and advantages will appear as the specification proceeds.

Heretofore it has been the practice to make half-tone silk screens photographically, i. e., by sensitizing the silk screen and exposing it to 20 line half-tone photo-plates, furnished by a photo-engraver, or to a shaded drawing on transparent material made by the Ben Day process. The making of photographic half-tone silk screens is not only a tedious and expensive process 25 requiring the use of fine silks, which are expensive and are often ruined by removing the sensitized solution with lye, but also, it requires a separate screen for each color to be printed. Furthermore, there is danger of obtaining moire- 30 effects by using line half-tones since the meshes of the silk form a screen too. In addition, the making of half-tone silk screens are limited to smaller sizes on account of the cost of photographic line half-tone plates and are also limited to one or two colors since the regular color 35 separation half-tone plates cannot be used in the silk screen process. The half-tone silk screens cannot use finer line half-tones than 60 to 70, and are therefore not used very much for 40 small work, while big reproductions for which 50 to 60 line half-tone would be perfectly suitable, cannot be made on account of the prohibitive cost of line half-tone plates of this size.

I have found that the photographic step can 45 be eliminated and good results obtained by a new method involving few and simple steps. My preferred method is as follows:

The sketch or enlargement is placed underneath the silk screen and a pencil tracing of the 50 sketch made on the screen by means of a lead pencil or other suitable means. I prefer to go quite into detail in order that the second step of shading with the wax crayon may be made easier. When the tracing is finished, the silk 55 screen is placed directly over a metal plate which

is deep-etched to provide raised shading dots, stipple, lines, or any desired design. The silk, carrying the tracing, rests directly upon the etched projections of the metal plate. The easiest way to produce distinct and different 60 shades is to use several plates having the same dot arrangement, but the dots being of different size on each plate. The artist then draws, with wax crayon, the picture on the screen just as though he were drawing on Ross-board or any 65 grained surface. Slight pressure with the wax crayon produces small dots or light shading on the screen, while stronger pressure produces larger dots. By slightly shifting the screen after each shading stroke, the number of dots can be 70 increased until the area becomes solid black (or another solid color). The artist works on the screen long enough until the crayon drawing appears like the original although somewhat 75 stronger in all values in order to be sure that enough wax is deposited on the screen.

After the drawing in wax has been completed, the screen is then prepared for printing by sealing all the open meshes in the silk with glue or some other suitable material. For example Le Page's 80 fishglue, slightly or more thinned down according to the number of mesh used, together with dye or watercolor to make it better visible, and with a little glycerine to give it greater flexibility, is now poured onto the screen around the edges 85 and with a sharp and straight cardboard scraped over the screen in every direction. In this manner, the glue is forced into every opening in the screen but, because of the resistance of the wax to the glue, it does not stand on top of the wax 90 drawing. After roughly drying, say for half an hour, the whole screen is washed with gasoline, turpentine, or other suitable solvent of the wax, and the wax quickly removed. Where the wax formerly stood, there are now fine openings varying in size. Since a glue screen is easily ruined by water, and is affected by moisture, it is advisable to give the screen a protective coat of silk screen lacquer. If desired, a coat of thin lacquer 95 may be sprayed onto the bottom of the screen. 100 For a stock screen and for very large runs, it is desirable to harden the glue by applying formalin and allowing it to dry on the screen. The lacquer may be applied after the application with the formalin.

105 Corrections on the screen can be made quite easily before the lacquer treatment by brushing with stiff brushes on places where stronger printing is desirable, or by spraying thin glue on places where fewer openings in the silk are required. 110

When it is desired to print in several colors, the foregoing process is modified slightly. The tracing is preferably made with ink instead of pencil. After the tracing is completed, the drawing is 5 worked out over the etched plate in exactly the same way as described above, except that the drawing now includes only the portions of the original in one color. After the completion of the shading with wax pencil, glue is applied, the 10 wax removed, and the glue hardened or covered with lacquer as described above. The printing is then carried on in the usual way. After the prints have been made, the glue is washed from the screen, leaving only the ink tracing thereon. 15 Another color portion of the original drawing is then shaded in with wax pencil and the same series of steps employed to effect the printing of the next color portion. In this manner, the prints in several colors can be readily formed 20 while employing the same screen. There is no limit to the number of colors which can be printed from one screen. By this method, fairly fine shading can be made with No. 10 or 12 silk, while finer silks like No. 15 or 16 produce shadings 25 equal to photographic work on No. 20 silk or finer. The easy cleaning of the screen and the easier printing through coarser silk especially on large jobs are a distinct advantage. The drawings do not have to be reversed but can be exactly like 30 the original.

I will now describe a modification of my process which gives greater accuracy in detail work. The process described above is the most practical for large work or where little detail is involved. 35 However, where greater accuracy in detail is required, I prefer to use the following method:

Instead of drawing directly on the silk screen with the wax crayon, I place a sheet of thin good tracing paper or high grade tissue paper upon 40 the original and make an outline tracing. The paper is then placed upon the etched metal plate and the drawing shaded in with wax pencil. By using a hard wax crayon and with the right pressure, every dot can be reproduced faithfully 45 and clear. When all the shading is finished, solid masses or lines can be added by drawing on a smooth surface.

The next step is to render the wax areas and lines opaque in order that the wax drawing may 50 serve as a negative. Upon a large sheet of white paper, I sprinkle gold bronze powder, or other suitable material, as evenly as possible over an area the size of the drawing. I then place the wax crayon drawing face down on the gold bronze 55 powder. My next step is to take a lukewarm iron and iron over the back of the drawing. Very little heat is required since the warm wax softens at about 120 or 130° F. It is undesirable to carry on the ironing operation for a long time because 60 this might cause spreading of the wax lines or dots. Adherence of the gold bronze to the wax renders the wax opaque and finishes the plate for exposure. The plate or negative is then exposed, just as in a photographic negative, to bring about 65 its reproduction upon the sensitized silk screen. This latter step being old and well known, further description is believed unnecessary.

If desired, my method may be employed to form the design in half-tone upon a paper sheet and 70 then a photograph may be taken of this drawing, and the photograph reproduced on a sensitized screen and plate, etc., in the usual manner. In this method, it is very desirable to use etched

plates with dots or lines from two to three times, or greater, the size required, so that the reduction by photographing will eliminate all roughness or inexactness.

While in the above description, I have given specific examples of one method of carrying out the invention, it will be understood that the details may be greatly modified without departing from the spirit of my invention. The foregoing detailed description has been given for clearness of understanding only, and no unnecessary limitations should be understood therefrom, but the appended claims should be construed as broadly as permissible, in view of the prior art.

I claim:

1. A process for the purposes sets forth, comprising tracing the outline of a drawing upon a silk screen, placing the screen over a roughened plate having raised projections extending over its face, shading in the drawing with wax pencil on the plate-supported silk to produce a half-tone effect, coating the silk with a wax-repellent material, removing the wax by means which does not remove the coating material, and printing upon a surface by forcing ink through said screen. 100

2. A process for the purposes set forth, comprising tracing the outline of a drawing upon a silk screen, placing the screen over and in direct contact with an etched plate having its surface covered with raised projections, shading in the 105 drawing with wax pencil on the plate-supported silk, coating the silk with a wax-repellent material, removing the wax, treating said coating material to strengthen it, and printing with said screen in the usual manner.

3. A process for the purposes set forth, comprising tracing the outline of a drawing upon a silk screen, placing the screen over a roughened plate having raised projections extending over its surface, shading in the drawing with wax pencil on the plate-supported silk to produce a half-tone effect, coating the silk with glue, removing the wax, treating said glue coating to strengthen it, and printing upon a surface by forcing ink 110 through said screen.

4. A process for the purposes set forth, comprising tracing the outline of a drawing upon a silk screen with ink, placing the screen over a roughened plate having raised projections, shading in a portion of the drawing with wax pencil 115 on the plate-supported silk, coating the silk with a wax-repellent material, removing the wax, printing upon a surface by forcing colored ink through said screen, removing the material on said silk, again placing the drawing over said 120 roughened plate, shading in another portion of the drawing with wax pencil, coating the silk with a wax-repellent material, removing the wax, and printing upon a surface by forcing a different colored ink upon said screen. 125

5. A process for the purposes set forth, comprising tracing the outline of a drawing upon a silk screen, placing the screen over a roughened plate having raised projections, shading in the drawing with shading-material on the plate-supported silk to produce a half-tone effect, coating the silk with a material repellent to said shading-material, removing the shading-material by means which does not remove the coating material, and printing upon a surface by forcing ink 140 through said screen. 145

FRANZ WEISS.
